SHELBY C. CHAPMAN, OF NEW YORK, N. Y., ASSIGNOR TO ELECTRICAL RESEARCH PRODUCTS INC., OF NEW YORK, N. Y., A CORPORATION OF DELAWARE

SOUND PICTURE SYSTEM

Application filed June 6, 1932. Serial No. 368,902.

This invention relates to sound pictures and particularly to a composite sound record, and has for one object the production of a sound film having two photographic sound records superimposed on the film to form one composite sound record.

Another object of this invention is the addition of a musical accompaniment to a synchronized speech film.

10 In the sound picture art, it is sometimes necessary to have the sound record made up of two sound records taken at different times. For example, it may be desired to have a musical accompaniment for a speech film, to add to the artistic appeal of the film or to fill in periods in which there is no speech. It is not practical to have the music recorded at the same time as the speech, due to the difficulty and expense of having the 15 musicians present in all of the locations in which the action is filmed. If the sound film, for example, is a newsreel of some important event, it would be impossible to have the musicians present, yet there might be 20 comparatively long periods of action without speech.

One method at present in use is to make a print of the sound film and project the picture, reproducing the speech through the 30 regular equipment. A musical accompaniment is played in synchronism with the action and the combined sound of the reproduced speech and the music recorded. A sound film is then made from the action film 35 and the combined sound record. This method, however, will result in a serious degradation of tone quality of the speech due to the accumulative errors of reproduction.

Another method heretofore suggested is 40 to have separate sound records on the two margins of the film, but this method requires two separate devices for changing the record into sound and unduly reduces the space on the film available for the picture.

45 In accordance with the present invention the action is filmed, a synchronized record of the speech taken at the same time, and the synchronized negatives cut and assembled in the desired order. A positive film 50 is made from the action negative and pro-

jected, while appropriate music is played and recorded in synchronism with the action. The action negative is then printed and on the same positive, the speech is printed, then by a double exposure, the music is 55 printed superimposed on the speech, the film developed, and printed, giving a commercial negative film having action pictures and a synchronized composite speech and music sound record.

60 In the drawing which shows one embodiment of this invention,

Fig. 1 represents a portion of the negative picture film;

Fig. 2 represents a portion of the speech 65 record on negative film;

Fig. 3 represents a positive print of the picture film;

Fig. 4 represents a portion of the music record;

Fig. 5 shows a positive print of the picture 70 film combined with the speech record;

Fig. 6 shows the film of Fig. 5 with a music record superimposed on the speech record.

In the production of a sound picture film 75 in accordance with this invention, the action is filmed in the usual manner and a synchronized record made of the accompanying speech. The negative films of the action and speech, which may be on the same or separate films, are then cut and edited, the final form having corresponding portions of the films in corresponding order. In Fig. 1, the final form of the picture film negative has been diagrammatically represented. In Fig. 80 85 2 the corresponding final form of the speech record negative has been represented, though it will be obvious that both these negatives may be combined on one film. The picture film negative is then printed, and in Fig. 3 90 the resulting positive film is diagrammatically represented. The speech record may be printed also on this positive though it is not required for the carrying out of this invention.

The picture film positive represented 95 in Fig. 3 is then projected in a room having suitable acoustic properties and in the presence of musicians, who play suitable music to accompany the action. A photographic sound record of the music is made, the move- 100

ment of this sound record film being synchronized with the movement of the picture film projecting the action. This negative sound record film of the music is represented in Fig. 4.

The picture film negative of the action Fig. 1 is then printed, and on the same positive film the sound record of the speech is printed, producing the positive film represented in Fig. 5.

This positive film is again passed through the printing machine, and the sound record of the music printed, superimposed on the sound record of the speech, to form a composite sound record. The positive film is then developed, and will show pictures of the action, accompanied by a composite sound record of both the speech and the music, synchronized with the action, as represented in Fig. 6.

The positive film Fig. 6 may then be used in a sound picture projector, to project pictures of the action. The sound record is reproduced by well known means to give speech synchronized with the action, and a musical accompaniment also synchronized with the action.

To produce duplicates of the positive film Fig. 6, the positive film is printed in the usual manner to make a negative film from which positive duplicates may be printed.

What is claimed is:

1. A photographic sound record comprising a composite photographic real image developed from a latent image forming a complete record of a sound and a second latent image forming a complete record of another sound, both said latent images being located in the same area.

2. The method of making a composite photographic sound record which comprises printing one sound record on a sensitive film then printing a second sound record on the same film superimposed on the first print to form one composite sound record and developing the film.

3. The method of adding a musical accompaniment to a talking motion picture film which comprises making a negative film of the action with the synchronized speech recorded thereon, making a separate negative film of the musical accompaniment, printing a positive film of the action and speech negative film, printing the music record on said positive film superimposed on the speech record, and developing the positive film.

4. The method of adding a synchronized musical accompaniment to a talking motion picture film which comprises making a negative picture film of the action, simultaneously making a negative film record of speech synchronized with the action, making a positive print of said action negative, projecting said positive print, making a negative film record of music played in synchronism with the projection of said positive print, printing

said action negative on a positive film, printing said speech negative on said positive film, printing said music negative on said combined speech record and picture film superimposed on the print of said speech negative and developing said positive film.

In witness whereof, I hereunto subscribe my name this 31st day of May, 1929.
